UNITED STATES PATENT OFFICE

128,062

DESIGN FOR SUNGLASSES

Rose Ehrlich, New York, N. Y., assignor to Lapin Products, Inc., New York, N. Y., a corporation of New York

Application November 25, 1939, Serial No. 88,489

Term of patent 14 years

To all whom it may concern:

Be it known that I, Rose Ehrlich, a citizen of the United States and residing at New York city, in the county of New York and State of New York, have invented a new, original, and ornamental Design for Sunglasses, of which the following is a specification, reference being had to the accompanying drawing, forming part thereof, and in which

Fig. 1 is a front elevational view of the front only of the sunglasses showing my design,

Fig. 2 is a top view of the complete sunglasses with the temple portions open to their fullest extent,

Fig. 3 is a side elevational view,

Fig. 4 is an inside perspective view of one of

the temple portions removed from the assembly as shown in Figs. 1 to 3, and

Fig. 5 is a transverse, sectional view of the prongs of the temple taken upon the line 5—5 of Fig. 4, upon an enlarged scale as compared to Fig. 4.

The characteristic features of my design for sunglasses reside in the specific configuration of the lens rims in combination with the bifurcated temples, the prongs of which are L-shaped in cross-section, as shown most clearly in Fig. 5.

I claim:

The ornamental design for sunglasses, substantially as shown and described.

ROSE EHRLICH.
